UNITED STATES PATENT OFFICE.

CHARLES GILLINGS, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed November 9, 1923, Serial No. 673,683, and in Great Britain December 19, 1922. Renewed February 14, 1929.

This invention relates in general to automatic telephone systems, but more especially to multi-exchange systems; and is an improvement in or modification of that set forth 5 in the co-pending application of Richardson et al. Serial No. 547,866, filed March 29, 1922. In that application, a multi-exchange system is described to which the first three letters of the name of the wanted exchange are 10 dialled to a so called "director" which translates them into the series of digits necessary for routing the call to that exchange.

The register controllers are divided into groups and the first letter dialled is arranged 15 to operate a group selector to pick out an idle register controller of a corresponding group, which then records the two other letters and the subscriber's number. In the above mentioned case, an arrangement is described in 20 which a director is released after sending the exchange digits if at that moment the subscriber has not yet started to dial the wanted number, so that the digits subsequently dialled pass direct from the calling line to 25 the wanted exchange.

The broad general object of the present invention is to provide certain facilities which have been found to be desirable when the system described in the main patent is applied 30 to a large telephone network. In such a network it will often happen that a number of classes of exchanges are found, differing in size. For instance, it is often the case that all the exchanges are not of 10,000 line capacity and in fact, some of the exchanges 35 may only have a maximum capacity of 1,000 lines, while others may only have a capacity of 100 lines. Consequently, in such cases it is not necessary to dial more than two or three 40 series of impulses corresponding to the number of digits in the number of the wanted party, and one of the features of the present invention relates to the provision of means by which when the necessary two or three digits 45 have been repeated by the register translating and sending apparatus this apparatus is automatically released.

According to another feature of the present invention, an arrangement is provided for 50 routing a call to an operator's position when an excessive pause occurs after the first or second and before the third letter of the exchange name has been called.

In certain cases it is advisable to entirely cancel the exchange code. For instance, there 55 may be exchanges where it is desirable to use certain levels of the first selector for giving access to trunk lines, while other levels are used for connecting up a subscriber local to the exchange, for instance, if the selector is 60 dialled to any of the first three levels it may gain access to second selectors and from second selectors to connectors and thence to the local subscriber. Consequently only four 65 digits altogether are required and the name of the exchange itself must be cancelled.

According to a further feature of the present invention, an arrangement is provided whereby the impulse registering, translating and sending apparatus does not send any 70 digits, but is released after the last letter in the exchange name has been dialled so that the digits dialled by the subscriber directly actuate all the switches.

It may be desirable, however, to store the 75 number digits in the usual manner, suppress the exchange code and repeat the stored digits before the sending apparatus is released.

A further feature of the present invention concerns a faulty-sender alarm circuit for informing the exchange attendant when a sender fails to send out impulses.

A still further feature concerns an arrangement for delaying the transmission of the exchange digits until all exchange and numerical digits have been dialled, this being particularly desirable when the call is routed to an exchange where there are no call indicator 85 positions and an operator completes the call.

In order that the invention may be clearly 90 understood and readily carried into effect, a telephone system in accordance with the invention will now be more fully described with reference to the annexed drawings in which:

Figures 1-5 inclusive are circuit diagrams 95 of sufficient of the apparatus used in a complete register translator system to illustrate the preferred form of the invention. These figures are based on Figures 1-5 of the above application.

The relay equipment D, first selector E', register selector or A impulse register F, Figure 1, the master digit controller MDS, thousands register M¹, hundreds register M², tens register M³, units register M⁴, Figure 2, 105 the impulse sending switch S, Figure 3, and

B and C impulse register J, the intermediate distributing frame IDF Figure 4 and the sequence switch S', Figure 5, are all identical with the corresponding apparatus in the main 5 patent and for that reason it is not thought necessary to again describe their operation in detail.

The general object and scope of the invention having been pointed out, the operation 10 of the apparatus involved will now be described more in detail, and for this purpose it will be assumed first that a calling party has taken into use the trunk conductors 10, 11, and 12, Figure 1 dialled the first three 15 letters of the exchange name and that the wipers 306-309, inclusive, of the B and C impulse register J are resting on bank contacts 500 in known manner. Bank contacts 500 correspond to a three figure exchange and it 20 is therefore necessary to operate the switching relay 112, Fig. 3, immediately the three numerical digits of the wanted party's number are sent i. e. when the sequence switch S' has reached the 8th position that is the wipers 25 are resting on the 8th bank contacts.

When the exchange code (i. e. the A, B and C digits) has been dialled the wipers 306-309 inclusive, are resting on bank contacts 500. The master digit controller MDS, Fig. 2 is 30 in 3rd position and extends earth over conductor 400, resting contact and armature 507 of relay 508, conductor 511, wiper 404 of sequence switch S' in 1st position, conductor 411, wiper 306 of register J, lower bank contact 500, make-before-break contacts controlled by armature 512, numerical digit cut-off relay 513 to battery. Relay 513 energizes in this circuit and closes a locking circuit for itself at armature 512 including conductors 514 and 102, bank contact 91 and test 35 wiper 87 of the register selector F, Fig. 1, armature 84 and its working contact, armature 74 and its working contact to earth.

When the exchange code translation and 40 the subscriber's number have been sent in the manner described in the application hereinbefore mentioned, the sequence switch S' steps to 8th position and the following circuit will be closed for switching relay 112, 45 Fig. 3; earth, armature 515 and its working contact, conductor 516, 8th contact in the bank of wiper 406 of sequence switch S', wiper 406, conductor 420, normally closed contacts controlled by armature 139, switching relay 112 to battery. Relay 112 operates 50 in this circuit and establishes at armature 139 a locking circuit for itself, opens at armature 140 the circuit of relay 107, removes at armature 137 the short circuit from resistance 141, 55 and at 136 disconnects conductor 103 from conductor 202 and connects 103 to earth. 60 This latter operation completes a circuit for the switching relay 13 in the first selector trunk as follows: earth, 136, 103, bank con-

tact 96, Fig. 1, 88, 83, 73, 62, contact springs 65 controlled by armature 16, relay 13 to battery. Relay 13 establishes at 16 a locking circuit for itself, connects at 14 and 18, trunk conductors 10 and 12 with conductors 20 and 22, respectively, and disconnects conductors 70 10 and 12 from conductors 60 and 61, respectively, at 15 and 17.

An instant after springs 14 and 18 engage their working contacts, the control circuit extending to the register translator is cut 75 off, and finally, just before the relay is fully operated, springs 15 and 17 disengage their resting contacts. The latter operation disconnects the line relay 64, and completes the switching operation by which the calling subscriber's line is connected through to the established connection. When line relay 64 of the register selector F is disconnected from trunk conductors 10 and 12 by relay 13, it breaks at 72 the circuit of slow release relay 80 65, which at 75 completes a circuit for release magnet 71, which restores the switch F to normal, the circuit of magnet 71 being opened at the off normal springs when the shaft reaches normal position.

Relay 65 disconnects earth from conductor 76 and from the holding conductor 102. Switching relay 68 and relays 110, 111, 112 and 210 also deenergize. Relay 111 connects earth at springs 133 and 133^a to the upper bank of switch S' in order to advance the sequence switch wipers to their normal position, earth being connected to armature 133^a as follows: armature 133^a, conductor 561, resting contact and armature 543 of relay 540 to earth. Relay 111 also connects at armature 132 wiper 113 of switch S with stepping magnet 115. This operation, however, is of no particular importance, ordinarily, owing to the fact that the sending switch is restored automatically by the completion of the same circuit at 116 of relay 105. Relay 110 connects earth at 130 to release conductor 204, thus completing parallel energizing circuits for release magnet 211 of the 100 master digit controller MDS, release magnet 305 of register J, and the release magnets 220, 221, 222 and 223 of register switches M¹, M², M³ and M⁴.

As described in the foregoing, the connection is switched through and the register translator is released as soon as the final series of impulses has been transmitted. The register translator is thus used only during the actual setting up of the connection and is 110 rendered accessible to other subscribers. As soon as the connection is completed and after the connection has been switched through, it is the same as an ordinary automatic connection.

The method of switching through to a two figure exchange will now be explained and for this purpose it will be assumed that the

exchange code has been dialled and that the wipers 306-309 inclusive, have been set on bank contacts 502. Bank contacts 502 correspond to a two figure exchange and it is therefore necessary to operate switching relay 112 immediately the two numerical digits have been sent, i. e., when the sequence switch S' has reached the 7th position. 5

When the wipers 306-308, inclusive, are resting on bank contact 502, the master digit controller MDS, Fig. 2 is in 3rd position and extends earth over the previously traced circuit to wiper 306 of register J, lower bank contact 502 make-before-break contacts controlled by armature 517, numerical digit cut-off relay 518 to battery. Relay 518 operates in this circuit and at armature 517 closes a locking circuit for itself including holding conductors 514 and 102. Relay 518 at 15 armature 519 connects earth over conductor 520 the 7th contact in the bank of wiper 406 of sequence switch S'. 20

When the exchange code translation and subscriber's number have been sent the sequence switch S' will step to 7th position and the earth on the 7th contact in the bank of wiper 406 will complete the previously traced energizing circuit for switching relay 112. Switching relays 112 and 13 operate as 25 before described to switch the calling party through and effect the release of the register controller. 30

It will be seen that the cross connection between the first bank contact of any two or 35 three figure exchange and the left hand side of the IDF, is taken through the contacts of the numerical digit cut-off relay to prevent that relay from being operated by any other combination which may have one of its bank 40 contacts cross connected to the same strip as the first bank contact of a combination which has to work to a two or three figure exchange. 45

From the foregoing it will be seen that an arrangement has been provided whereby two, 50 three and four figure exchange systems in the same net work are adapted to be controlled from the same impulse registering, translating and sending apparatus without it being necessary to prefix the two and three figure exchange numbers by two and one digits respectively. 55

A description of the method of routing a calling subscriber to an operator's position and releasing the register controller for further service should a pause of sufficient duration occur after the first or the first and second and before the third letter of the wanted exchange name has been dialled, will now be explained. 60

Referring now to Figure 2, the timing cam T is mounted on a constantly rotating shaft which makes one complete rotation every thirty seconds, and consequently, as soon as this cam earths conductor 299 a circuit is completed for the upper winding of pick up relay 65

206 as follows: earthed conductor 299, armature 209 and its working contact, armature 521 and its resting contact, upper winding of relay 206 to battery. Relay 206 partially operates and closes contacts 522 only. 70 When the earth has been removed from conductor 299, relay 206 fully operates in the following circuit: earth, armature 215 and its resting contact, working contact and armature 217, armature 522 and its working 75 contact, upper and lower windings of pick up relay 206 in series to battery.

Relay 206 upon operating performs the following functions: 80

1. Closes a circuit at armature 523 for the upper winding of relay 205 from earth, wiper 219 of master digit control switch MDS in position 1 or 2, conductor 524, armature 523, upper winding of relay 205 to battery. This relay, being adjusted so that the combined 85 energization of both of its windings is required to operate it, does not operate because its lower winding is disconnected by earth being removed from conductor 299. 90

2. Prepares the following circuit at armature 521 for switching relay 112, Fig. 3: armature 521 and its working contact, armature 525 and its resting contact, conductor 201, conductor 420, normally closed springs controlled by armature 139, winding of slow 95 switching relay 112 to battery. 100

Relay 206 also prepares at armature 521 and its working contact a circuit for the lower winding of relay 205. After a predetermined time the timing cam T again earths conductor 299 and relay 205 energizes and at armature 526 completes the following locking circuit for itself: battery, lower winding of relay 205, armature 526 and its working contact to earthed holding conductor 514. Relay 205 upon energizing earths the start lead 511 from earth, wiper 219 of master digit control switch MDS in position 1 or 2, conductor 524, armature 527 and its working contact, conductor 400, back contact and armature 507, start conductor 511, back contact and armature 509, wiper 405 of sequence switch S' in first position, conductor 425, back contact and armature 119, armature 140 and its resting contact, impulsing relay 107, interrupter I to 115 battery. The translation now takes place in accordance with the cross connections from terminals 342-346. Relay 205 also connects the left hand terminals 346-342 of the IDF, via conductors 528-532 working contacts and armatures 533, conductors 534-538, conductors 411-415 to contacts 1 to T inclusive in the bank of wiper 404 of sequence switch S'. The cross connections from terminals 342-346 of the IDF, are only typical and 120 represent a three figure translation 123. 115

Immediately relay 205 operates the circuit of switching relay 112 is broken at armature 525, but in order to ensure that relay 112 does not operate a small copper slug is placed on 130

the armature end of the core. This copper slug momentarily delays the operation of relay 112.

When the translation has been sent the circuit of switching relay 112 is completed as follows: battery, winding of relay 112, make-before-break contacts controlled by armature 139, conductor 420, wiper 406, conductor 373, terminal SW¹, terminal 345, conductor 529, 10 armature 533, conductor 537, conductor 414, bank contact 4 in the bank of the wiper 404 of sequence switch S', wiper 404, conductor 511, armature 507 and its resting contact, conductor 400, working contact and armature 527 of 15 relay 205, bank contact 1 or 2 of master digit control switch M, wiper 219 to earth.

Switching relays 112 and 13 cause the connection to be switched through to the 1st selector E' and the release of the register translator for further service.

Should a pause of sufficient duration occur after the third letter of the exchange name has been dialled the operation as described in the main patent takes place and relay 205 is 25 not operated as the master digit control switch is in 3rd position and therefore only one winding of the relay 205 is energized.

The small copper slug on relay 112 momentarily delays its operation but in no way interferes with the general operation of the circuit.

A description will now be given of an arrangement whereby the exchange code can be cancelled and the subscriber's number only 35 made effective. The register translator when modified as described below, is made to cancel the exchange code, and to switch the call through to the 1st selector E' which then responds to the dialled impulses, thus illustrating 40 that 1st, 2nd or 3rd selectors in a system using register controllers can be made to respond to either exchange codes, as translated, or directly to dialled impulses as required by the trunking scheme.

45 In cases where it is clear that growth beyond 900 numbers will not be required for a given office, it is possible to operate this office with register translator equipment and 1st selectors only. For "branch" office working 50 all outgoing traffic is routed over one level of the 1st selectors say "0". All exchange names are translated in this office, so that this is the first digit sent,—other digits being such as to secure the correct routing of a call in the main office. The remaining 9 levels of the 1st selector are used for trunks direct to connectors giving 900 numbers. The exchange code when dialled cuts off the register translator and leaves the call through to the 1st selector 55 which responds directly to impulses from the dial in the usual way. Subscribers numbers in this case consist of the exchange code and 3 digits only, irrespective of the fact that this office is part of a large network.

60 65 An alternative plan provides that both the

exchange code and the subscriber's number are received by the register translator, but that the code is cancelled and only the numerical part of the subscriber's number set out.

Assuming that the exchange code has been 70 dialled and that the wipers of the switch J are set on bank contacts 504 then the following energizing circuit for switching relay 112 is completed. Earth, wiper 219 of master digit control switch MDS in 3rd position, conductor 400, back contact and armature 507, conductor 511, wiper 404 in normal position, conductor 411, wiper 306 of switch J, lower bank contact 504, conductor 539 to wiper 406 where it joins conductor 420, make-before-break contacts controlled by armature 139 to switching relay 112 and battery. Relay 112 closes a locking circuit for itself and causes the switching relay 13 to operate and switch the connection through to the selector E'. 85 The register controller is released in the hereinbefore described manner and subsequent digits dialled operated standard Strowger switches in the usual manner.

A description will now be given of the alternative arrangement in which both the exchange code and subscriber's number are received by the register controller, the exchange code being cancelled and the numerical digits being transmitted by the register. For this purpose we assume that the exchange code has been dialled and that the wipers of switch J are set on bank contacts 505 and that the master digit switch is in third position. When wiper 306 of switch J engages the lower bank contact 505 the following circuit is completed for relay 540: battery relay 540, make-before-break contacts controlled by armature 541, conductor 542, lower bank contact 505, wiper 306, conductor 411, and over the previously traced circuit to wiper 219 of the master digit control switch M in third position and earth. Relay 540 energizes in this circuit and closes the locking circuit for itself at armature 541. At armature 542 100 opens the circuit of relay 111 in the sender S which releases and earths at armatures 133 the first three contacts in the bank of wiper 403 of switch S'. Relay 540 at armature 543 earths conductors 544 which causes magnet 402 of sequence switch S' to automatically advance to fourth position which is the position for controlling the numerical digits from the register translator in the usual way. 110

It will be appreciated that the register translator can translate the exchange code, i. e., the first three letters of the exchange name, to operate any number of trunking switches from nil to four, and in addition can store and send subscribers' numbers using any number of digits up to four or can function without subscribers' numbers. Any combination of code and number within these limits being possible.

120 125 130 A description will now be given of the

method of delaying the transmission of the exchange digits until all exchange and numerical digits have been dialled, and for this purpose we will assume that the wipers of switch J are set on bank contacts 506 corresponding for instance to a manual exchange without a call indicating position. Consequently, as soon as earth is placed on wiper 306, relay 508 is energized and locks energized 5 the holding contact on lead 514. Relay 508 at armature 507 opens the connection of lead 400 to lead 511 thereby preventing the sender being started due to earth being placed on the third contact of master digit control switch 10 M. In order to ensure that the starting circuit will be broken before relay 508 is energized an auxiliary sluggish relay 510 is connected to the lead 524 and therefore maintains at 509 the connection between lead 511 15 and its starting branch open for a sufficient time to allow relay 508 to energize and open the connections at back contact of armature 507.

The front contact of armature 507 is connected to lead 550 which is connected to lead 424 which is connected to earth only after the last numerical digit has been registered. Consequently the starting of the sender over lead 511 is delayed until the last series of 25 impulses have been registered.

It might happen that if a sender becomes faulty for any reason no impulses are sent out when an alarm should be given to attract the attention of the exchange attendant as 30 distinct from the attention of an operator in the case of a fault on the part of a calling subscriber.

For this purpose a second pick up relay 551 Fig. 2, is provided which is controlled in a 35 similar manner to pick-up relay 206 whenever relay 210 is energized.

The initial energizing circuit extends from earth on springs of timing cam T, conductor 229, armature 209 and its front contact, conductor 552, armature 553, and its back contact, lower winding of relay 551 to battery.

Relay 551 partially energizes and prepares a circuit at its armature 554 through armature 555, conductor 556, armature 557, 40 conductor 558, conductor 511 to armature 507 which is connected either to lead 400 or to lead 550 according as to whether relay 508 is energized or not. In either case it will be recollected that earth is connected to this armature when the sending is to commence so that relay 551 will fully energize when the earth connection is removed from armature 553 if the conditions are such that the sender start circuit is incompletely as determined by earth 45 connection to armature 507 and the sender has not commenced to send impulses as determined by relay 106. If the sender commences to operate relay 106 will energize and allow relay 551 to fall away. If, however, 50 the sending is delayed for half a minute or as

determined by the timing cam T a unit will be completed for relay 559 which locks energized and can only be released manually by key 560 and completes a circuit at armature 562 for the alarm 563.

What is claimed is:

1. In a telephone system, a plurality of register senders including registering mechanism to register telephone numbers and sending mechanism to control switching mechanism to complete connections in accordance with the registered numbers, switching mechanism for extending a connection from a calling line to one of said register senders responsive to the dialling of a pre-determined digit, a timing device thereupon effective to cause the sending mechanism of said register sender to transmit a pre-determined digit combination at the end of a pre-determined time, and means responsive to further dialling by the calling subscriber for preventing said timing means from exercising said control of the sending mechanism.

2. In a telephone system, a plurality of register senders including registering mechanism to register telephone numbers and sending mechanism to control switching mechanism to complete connections in accordance with the registered numbers, switching mechanism for extending a connection from a calling line to one of said register senders, a timing device thereupon effective to cause the sending mechanism of said register sender to transmit a pre-determined digit combination at the end of a pre-determined time, controlling means responsive to further dialling on the part of the calling subscriber to prevent the said timing means from effecting the said control of the sending mechanism, and means controlled by the timing means rendered effective responsive to said further dialling to free the register sender and to place the further extension of the connection under the direct control of the calling subscriber at the end of a pre-determined time.

3. In a telephone system, a plurality of register senders including registering mechanism to register telephone numbers and sending mechanism to control switching mechanism to complete connections in accordance with the registered numbers, switching mechanism for extending a connection from a calling line to one of said register senders, a timing device thereupon effective to cause the sending mechanism of said register sender to transmit a pre-determined digit combination at the end of a predetermined time, controlling means responsive to further dialling on the part of the calling subscriber to prevent the said timing means from effecting the said control of the sending mechanism, and means controlled by the timing means rendered effective responsive to said further dialling to free the register sender and to place the further extension of the connection under the direct control of the calling subscriber at the end of a pre-determined time.

4. In a telephone system, a plurality of register senders including registering mechanism to register telephone numbers and sending mechanism to control switching mechanism to complete connections in accordance with the registered numbers, switching mechanism for extending a connection from a calling line to one of said register senders, a timing device thereupon effective to cause the sending mechanism of said register sender to transmit a pre-determined digit combination at the end of a predetermined time, controlling means responsive to further dialling on the part of the calling subscriber to prevent the said timing means from effecting the said control of the sending mechanism, and means controlled by the timing means rendered effective responsive to said further dialling to free the register sender and to place the further extension of the connection under the direct control of the calling subscriber at the end of a pre-determined time.

direct control of the calling subscriber at the end of a pre-determined time, said controlling means being responsive to still further dialling to prevent the said operation of the 5 last named means.

4. In a telephone system, a register sender including two registers and sending mechanism controllable thereby, automatic switching mechanism for extending a calling line to 10 said register sender, other automatic switching mechanism for subsequently completing the connection to a called line under control of said register sender, delay-action means operative subsequent to the seizure of said 15 register sender to control said sender to transmit a pre-determined digit combination, and means operated by the receipt of the impulses transmitted from the calling line to operate the first of said registers to cancel said 20 control of said delay action means over said sender.

5. In a telephone system, a register sender including two registers and sending mechanism controllable thereby, automatic switching mechanism for extending a calling line to 25 said register sender, other automatic switching mechanisms for subsequently completing the connection to a called line under control of said register sender, delay-action 30 means operative subsequent to the seizure of said register sender to control said sender to transmit a pre-determined digit combination, means for releasing the sender and for placing the further extension of the connections 35 under the direct control of the calling line, and means operated by the receipt of the impulses transmitted from the calling line to operate the first of said registers to cancel said 40 control of said delay action means over said sender and to place said releasing means under the control of the delay action means.

6. In a telephone system, a register sender, exchanges of different classes, and a relay in 45 said register sender operated responsive to the exchange registering mechanism being set in a certain position to record the class of the called exchange corresponding to such position and to control the sender in transmitting a digit determined by the setting of said 50 register mechanism.

7. In a telephone system, a register sender, exchanges divided into a plurality of classes, and a relay in said register sender common to all the exchanges in a particular class operated responsive to the setting of the exchange 55 registering mechanism into the position assigned to any one of said exchanges of the said particular class to effect a circuit change in the register sender to adapt said register 60 sender to handle calls to that class of exchange, and to control the sender in transmitting one of the digits required to trunk the call to the particular called exchange.

8. In a register sender for use in multi- 65 exchange telephone systems in which a dis-

tinct setting position is provided for every exchange, a switching device controlled responsive to said register sender being set in certain of said distinct setting positions to alter the time at which the sending operation 70 takes place.

9. In a register sender for use in telephone systems in which a distinct setting position is provided for every exchange in the net work, and in which retransmission of impulses begins before the complete number is registered, a switching device operated responsive to said register sender being set into certain of said distinct setting positions to make starting of the retransmission of the 75 impulses dependent upon the receipt of the last digit in the number.

10. In a register sender for use in telephone systems, means for registering the digits in a telephone number, means for operating the 80 sending mechanism to retransmit digits in accordance with said registration, an alarm circuit, a timing device for closing said circuit, and means responsive to the operation of the sending apparatus in retransmitting 85 digits for preventing said timing device from closing the alarm circuit.

11. In a telephone system, a register sender including an office register and a plurality of other registers, means for setting said office register into a position corresponding to the office digits of a telephone number and for setting said other registers into positions, respectively, corresponding to the remaining digits in said telephone number, sending 90 mechanism controlled by said office register to transmit digits to trunk the call to the desired office and controlled by said other registers to transmit digits to complete the connections, and means responsive to a particular setting of said office register for canceling 95 said control of said office register over the sending mechanism.

12. In a register sender employing a sender controlled in turn by each of a plurality of registers, a control relay connected between a particular setting of one of said registers and said sender, a circuit for energizing it when said one register is set in said particular position, and contacts on said relay for closing a local locking circuit for said relay, and for disconnecting the first named circuit from said relay, and for extending it to said sender, whereby said sender is controlled in the usual manner by said register and said locking circuit does not interfere with the 100 subsequent sender operation.

13. In a director, a register, a sender including a counting device, contacts in the bank of said register connected to said counting device, another contact in said bank extending to a relay, and contacts on said relay for extending said other contact to said counting device.

14. In a director, a register, a sender in-

cluding a counting device, contacts in the bank of said register connected to said counting device, another contact in said bank extending to a relay, contacts on said relay for 5 extending said other contact to said counting device, and other contacts on said relay controlling the release of said director.

15. In a telephone system comprising exchanges of different sizes and in which the 10 number of digits in the telephone numbers are not uniform, a director for trunking calls to said exchanges and to lines therein, calls to each exchange being extended in accordance with a different code, director cut off 15 relays, one for each exchange except those exchanges having a maximum number of digits in their numbers, and a register contact assigned to each exchange for determining a digit of the code and for operating the corresponding 20 cut off relay.

16. In a telephone system, two exchanges, subscribers' lines in the second exchange having more digits in their telephone numbers than the lines in the other exchange, a 25 third exchange, a director in the third exchange for trunking calls to either of said first two exchanges in accordance with office codes and for controlling the completion of such calls in the exchanges, means for automatically 30 releasing said director responsive to the transmission of the final digit in the number of a subscriber in the second exchange, a conductor in said director for determining the value of a code digit in the first 35 exchange code, and a relay energized over said conductor for enabling said director to release after the transmission of the final digit in the number of a subscriber in the first exchange.

40 17. In a director, a register, a sending mechanism including a counting device, a control relay, a connection from a given contact in said register to a contact in said sender independent of the contacts of said relay, a 45 connection from a second contact in said register to a contact in said sender through contacts on said relay, and means controlled through the last named register contact for operating said relay to complete the last said 50 connection.

18. In a director, a register, a sending mechanism including a counting device, a control relay, a connection from a given contact in said register to a contact in said sender independent of the contacts of said relay, a 55 connection from a second contact in said register to a contact in said sender through contacts on said relay, means controlled through the last named register contact for operating said relay to complete the last said 60 connection, and other contacts on said relay to disconnect it from the associated register contact.

65 19. In a telephone system, automatic switches for connecting a calling and called

line, a director for controlling said switches and including means for registering the number called, and means in said director responsive to a delay in dialling for either operating certain of said switches according to 70 a predetermined code or for connecting the calling line with the first of said switches, depending on whether the delay occurs before or after a certain definite digit of the number is dialled. 75

20. In a telephone system, automatic switches for connecting a calling and a called line, a director for controlling said switches and including means for registering the number called, and means in said director responsive to a delay in dialling for either 80 operating the director to set one of said switches independent of any registration or for immediately restoring the director to common use, depending on whether the delay 85 occurs before or after a certain definite digit of the number is dialled.

21. In a register sender for use in telephone systems, means for registering the digits in a telephone number, means for operating the sending mechanism to retransmit digits in accordance with said registration, a time controlled alarm circuit, and means controlled by said sending mechanism while 90 in operation for opening said alarm circuit. 95

22. In a register sender for use in telephone systems, means for registering the digits in a telephone number, a sending mechanism including a counting switch, means for operating said sending mechanism and said 100 counting switch to retransmit digits in accordance with said registration, an alarm circuit, a timing device for closing said alarm circuit, and means operative responsive to said counting switch moving off normal for 105 opening said alarm circuit.

23. In a telephone system, a register sender including an office register, means for setting said office register into a position corresponding to the office digits of a telephone number, a step by step sequence switch, sending mechanism controlled jointly by said office register and said sequence switch to retransmit digits to trunk the call to the desired office, and a 110 relay, said relay operated responsive to a particular setting of said office register for causing said sequence switch to operate and cancel the control of said office register over 115 said sending mechanism.

24. In a telephone system, a register sender including an office register and a plurality of other registers, means for setting said office register into a position corresponding to the office digits of a telephone number and for setting said other registers into positions, respectively, corresponding to the remaining digits in said telephone number, a step-by-step sequence switch, sending mechanism initially controlled jointly by said office register and said sequence switch to trans- 120 125 130

mit digits to trunk the call to the desired office and then controlled jointly by said other registers and said sequence switch to transmit digits to complete the connection, a relay, and means for operating said relay responsive to a particular setting of said office register for causing said sending mechanism to start operation under the joint control of said sequence switch and the said other registers.

25. In a telephone system, a director comprising means for registering a telephone number and for transmitting a series of digits including both office and line selecting digits, a switching device in said director having a position for each of said digits, means for automatically advancing said device past all the positions which correspond to office selecting digits in case a telephone number in a particular office is called, and means for preventing the transmission of any digits while the automatic advance of said device is taking place.

26. In a telephone system, a registering mechanism for registering the digits in a telephone number, a sender for retransmitting the digits registered on said registering mechanism, a circuit for starting the operation of said sender, means normally effective to close said circuit when part of the digits of a telephone number have been registered, a relay, and means for operating said relay to prevent the closing of said circuit in case certain digits have been registered on said registering mechanism.

27. In a telephone system, a registering mechanism for registering the digits in a telephone number, a sender for retransmitting the digits registered on said registering mechanism, a circuit for starting the operation of said sender, means normally effective to close said circuit when part of the digits of a telephone number have been registered, a relay, means for operating said relay to prevent the closing of said circuit in case certain digits have been registered on said registering mechanism, a second circuit for starting the operation of said sender, and means dependent upon the receipt of the last digit in the telephone number for closing said second circuit to start said sender.

28. A register sender for use in a telephone system wherein the digits of a telephone number are registered on a register-

ing mechanism, and in which a sender normally starts to retransmit part of the digits before all of the digits of a telephone number have been registered, characterized in this, that there is means operative for delaying the starting of the sender until the registering mechanism receives the last digit of the telephone number in case certain digits are registered on the registering mechanism.

29. In a director, a sender for retransmitting a plurality of digits, a sequence switch having a position for each digit, director cut-off means operated in a particular position of said switch, a relay, and means for operating said relay to control the sender in retransmitting a digit and to cause said cut-off means to operate in a different position of said switch.

30. In a telephone system, a director, a sender for transmitting a plurality of digits, a sequence switch having a position for each digit, director cut-off means operated in a particular position of said switch, exchanges of different classes, a relay for each of said classes, and means for operating one of said relays when a call is to be extended to an exchange of one of the classes to control the sender in retransmitting one of the digits to trunk the call to the particular called exchange and to cause said cut-off means to operate in a different position of said switch.

31. In a telephone system, a director, a sender for transmitting a plurality of digits, a sequence switch having a position for each digit, director cut-off means operated in a particular position of said switch, exchanges of different classes, a relay for each of said classes, means for operating one of said relays when a call is to be extended to an exchange of one of the classes to control the sender in retransmitting one of the digits to trunk the call to the particular called exchange and to cause said cut-off means to operate in a different position of said switch, and means for operating another of said relays when a call is to be extended to an exchange in a different class to control the sender and to cause said cut-off means to operate in another different position.

In witness whereof, I hereunto subscribe my name this twenty-third day of October, 1923.

CHARLES GILLINGS.
